C. KEMP.

LOCK

APPLICATION FILED OCT. 18, 1918.

1,300,844.

Patented Apr. 15, 1919.

UNITED STATES PATENT OFFICE.

CHARLES KEMP, OF NEW YORK, N. Y.

LOCK.

1,300,844.

Specification of Letters Patent. Patented Apr. 15, 1919.

Application filed October 18, 1918. Serial No. 258,701.

To all whom it may concern:

Be it known that I, CHARLES KEMP, a citizen of the United States, and a resident of the borough of Manhattan, city, county, and 5 State of New York, have invented certain new and useful Improvements in Locks, of which the following is a specification.

My improvements relate to locks generally, but are designed more particularly for 10 locks for doors and similar closures. The main object is to afford a simple but strong and durable lock of few parts; in which all the operative parts are protected and concealed when in locked position, and which is 15 practically jimmy proof,—the invention consisting in the specific construction and arrangement of parts described and claimed herein, a distinctive feature being the means whereby a duplex bolting effect is attained, 20 all as hereinafter more fully set forth.

In the accompanying drawings,

Figure 1, is a top view of my improved lock, with the cover plate removed;

Fig. 2, is a view of the inner side of the 25 cover plate;

Fig. 3, is a section taken upon plane of line 3—3, Fig. 1;

Fig. 4 is a section taken upon plane of line 4—4, Fig. 3;

Fig. 5, is an elevation of the inner side of 30 the bolt rack bar;

Fig. 6, is an elevation thereof taken at right angles to Fig. 5;

Fig. 7, is an elevation of the open side of 35 the hasp cylinder;

Fig. 8, is an elevation of the staple piece;

Fig. 9 is an end elevation of the latch 40 spindle;

Fig. 10, is a side elevation thereof;

Fig. 11, is a side elevation of the latch 45 knob or handle;

Fig. 12, is an end view of the key arbor;

Fig. 13, is a side elevation thereof.

The casing consists of the base plate C, 45 shell C', and cover plate C''. The shell C', and base plate C, are spaced apart in a manner well known in the art by posts c, c, on the base plate C, which latter is screwed or otherwise rigidly secured to the door or 50 other closure to be protected. A boss c', (Fig. 3) on the shell C', is formed with a socket c'', for the accommodation of one trunnion h, of the hasp cylinder H, the other trunnion h', of said hasp cylinder H, 55 being fulcrumed in a corresponding socket

c'', in a boss c', on the inner side of the cover plate C''.

The hasp cylinder H, is essentially hollow in that it is formed with the longitudinal recess h², and lateral slots h³, opening thereinto for the accommodation of the arms s, s, and cross bar s' of the staple S, as will be understood by reference more particularly to Figs. 1 and 4, of the drawings.

The staple S, is protuberant from an angular base plate S', which is secured to and countersunk in the jamb J, of a door frame or the like as indicated in Figs. 1 and 4,—the lock as before intimated being secured by its base plate C', to the door or other closure 65 D, and it is secured thereto in such manner that the end of the casing in which the hasp cylinder H, is mounted will overlap the staple S, and its plate S', when the door or other closure is turned to closed position. 70 It is to be noted in this connection that edge c'', of the base plate C, at this end of the lock terminates short of the edge c'', of this end of the shell C', so as to leave an opening 75 in the lock casing through which the staple 80 S, may project when the hasp cylinder H, is in proper position to receive said hasp.

The peripheral surface of the medial portion h⁴, of the hasp cylinder H, between the opening h², and lateral slots h³, h³, is formed with teeth h⁵, for engagement with rack teeth b, formed for the purpose on the adjacent outer end b', of the bolt bar B, the rear portion of which is formed with two series of rack teeth, one series b², for engagement with peripheral teeth l, on the annular rollback or boss l', of the latch spindle L, and the other series b³, for engagement with the peripheral teeth k, on the annular disk k', of the key arbor K. 90

The forward end of the rack bolt bar B is held against lateral movement by guards c⁵, c⁵, (Figs. 1 and 3) on the base plate C, while the rear portion of said bolt rack bar is held against lateral movement on one side 100 by the guard c⁶, also on the base plate C, and by its contact on the other side with the aforesaid annular rollback or boss l', of the latch spindle L, and with the disk k', of the key arbor K, as will be understood by reference more particularly to Fig. 3.

The key arbor K, and the latch spindle L, are positioned in axial alinement, but are not connected with each other, the latch spindle L, being journaled on the shell plate 110

C', while the key arbor K, is journaled on the base plate C, as shown more particularly in Fig. 4,—the annular disk k' , of the key arbor resting against the annular rollback or boss l' , of the latch spindle L. l^2 , is the handle of the latch spindle L, formed with the angular stem l^3 , fitting in a correspondingly formed socket l^4 , in the latch spindle L, and secured thereto. Thus by means of 10 this knob or handle l^2 , the latch spindle may be turned to reciprocate the rack bolt B. The key arbor in like manner is turned by means of a suitable key inserted in the key hole k^x , of the arbor K, it being understood 15 that said arbor represents symbolically any of the key arbors or equivalent devices known in the art.

In order to hold the latch spindle L, in prescribed position with its teeth l , either in 20 or out of engagement with the teeth b^2 , of the rack bolt B, I form said latch spindle L, with a duplex cam l^5 , and provide a fixed flat spring m, the free end of which bears against said duplex cam l^5 , with sufficient pressure 25 to normally hold the latch spindle either in the position shown in Fig. 2, or in an intermediate position in which the latch spindle is turned to bring one of the apices of the cam into contactual engagement with said 30 spring m,—the latter yielding before the protuberant cam surfaces. In other words it is obvious that if the latch spindle L, is turned to bring the duplex cam l^5 , at substantially right angles to that shown in Fig. 35 2, the spring m, at dead center will tend to hold the latch spindle in such position.

As before intimated, although the latch spindle and the key arbor are in axial alinement they are independently rotatable upon 40 their axes. Hence either may be used to reciprocate the rack bolt B, to make or break connection between the hasp cylinder H, and the bolt B, and the staple S,—the spur teeth l , on the latch spindle L, being out of coincidence with the spur teeth k , on the key arbor. A ratchet spring r, may be provided for engagement with the peripheral teeth h^5 , of the hasp cylinder H, of sufficient elasticity to admit of the turning of said cylinder by the 45 rack bolt while tending constantly to steady and hold said cylinder against play or looseness.

As will be understood by reference to Figs. 1 and 4, particularly that when the rack bolt 50 B, is shot to locking position the action of the hasp cylinder in engaging the cross bar s' , of the staple is supplemented and reinforced by the outer end of the said bolt itself

which also enters the staple, thus effecting a dual locking of the parts that effectually prevents the forcing or "jimmying" of the lock by ordinary known means short of the actual destruction of the lock or the door or other closure sought to be protected. Furthermore 60 all the operative parts of the locking mechanism are inclosed and isolated when connection is made with the staple; and the parts are simple, inexpensive and not liable to derangement under ordinary conditions 65 of use. 70

What I claim as my invention and desire to secure by Letters Patent is,

1. In closure means of the character designated, in combination with a jamb staple or equivalent stationary securing means, a lock comprising a rotatable hasp cylinder adapted to engage with said staple and formed with peripheral teeth, a rack bolt formed with teeth engaging said cylinder teeth, and with two other series of rack teeth, one set 80 engaging and actuated by teeth on a key arbor, and the other set engaging and actuated by teeth on a latch spindle, together with said toothed key arbor and said toothed latch spindle, for the purpose set forth. 85

2. In closure means of the character designated, in combination with a jamb staple or equivalent stationary securing means, a lock comprising a rotatable hasp cylinder adapted to engage with said staple and formed with 90 peripheral teeth, a rack bolt adapted to engage with said staple and formed with teeth engaging said cylinder teeth, and also formed with two other series of rack teeth, one set 95 engaging and actuated by teeth on a key arbor, and the other set engaging and actuated by teeth on a latch spindle, together with said toothed key arbor and said toothed latch spindle, for the purpose set forth.

3. In closure means of the character designated, in combination with a jamb staple or equivalent stationary securing means, a rack bolt adapted to engage with said staple and formed with two series of rack teeth, one set 100 of said rack bolt teeth engaging and actuated by teeth on a latch spindle, the other set of said rack bolt teeth engaging with and actuated by teeth on a key arbor, said key arbor formed with a cam, a dead center 105 spring detent contactually engaging said 110 cam, and said latch spindle, for the purpose described.

CHARLES KEMP.
